UNITED STATES PATENT OFFICE

2,359,254

SEAT OPERATED SWITCH

Orville Kenneth Silver, Detroit, Mich.

Application April 8, 1943, Serial No. 482,296

1 Claim. (Cl. 200—85)

This invention relates to new and useful improvements in seat operated switches for use in electrical systems for indicating the presence of vacant seats in a theater.

An important object of the invention is to provide a positive acting and substantially fool-proof switch structure for seats for use in conjunction with an electrical indicating means to indicate when the seat is not occupied.

A further object of the invention is to provide a switch from which sparks cannot be emitted and which would frighten patrons in a theater or perhaps cause a combustion in the event combustible vapors were adjacent, if it were not for the precautionary features involved.

Other objects and advantages of the invention will become apparent to the reader of the following description.

In the drawings—

Figure 1 represents a side elevational view of a theater seat, showing in dotted lines the switch.

Figure 2 is a side elevational view of a theater seat with the seat section in elevated position and the switch, which is in dotted lines, shown in open position.

Figure 3 is a top plan view of the structure shown in Figure 1.

Figure 4 is an enlarged detailed sectional view taken substantially on the line 4—4 of Figure 1.

Figure 5 is an enlarged fragmentary detailed sectional view taken substantially on the line 5—5 of Figure 3.

Figure 6 is a fragmentary bottom plan view of the seat section showing one of the contact elements.

Figure 7 is a fragmentary top plan view showing one of the seat supporting ledges of the chair and contact means thereupon complementary to the contact means shown in Figure 6.

Figure 8 is a diagrammatic view showing the electrical connections between the electrical elements involved.

Referring to the drawings wherein like numerals designate like parts, numeral 5 generally refers to a substantially conventional theater chair which includes side portions 6, 6, a back section 7 and inwardly disposed ledges 8 on the side portions 6 to support a swingable seat section 9 which is swingably supported as at 10. Suitable spring means 11 serves to hold the seat 9 in raised position as shown in Figure 2, when the seat is not occupied in order to maintain a switch 12 open.

Referring more specifically to the seat section 9, adjacent one side portion of the bottom thereof, an inset 13 is formed, to the top wall of which is secured a ring 14 of current conducting material held against a disk 15 of insulation by a bolt 16, this bolt 16 passing through a washer 17 overlying the central portion of the ring 14 and being equipped with a nut 18 to hold the last-men-

tioned parts in place as suggested in Figures 5 and 6.

On one ledge 8 is a laterally disposed and curved protrusion 19 upon which sets a cup 20 of insulation. A plate 21 of suitable insulation is placed upon the bottom of the cup 20 and has secured thereon a pair of short arcuate-shaped spring contact members 23, 24, from which conductors 25, 26 extend.

10 When the seat 9 is in lowered position as shown in Figure 5, the contacts 23, 24 will bear against the contact ring 14, thus closing a circuit due to the fact that the ring 14 acts as a bridge between the contacts 23, 24.

15 When the seat 9 is lowered the well will encompass the cup 20 as the depending contact 14 moves into the cup to contact the contact elements 23, 24. Thus, it is practically impossible for a spark to escape to a point beyond this 20 switch assembly.

Referring to Figure 8, numeral 27 denotes a current supply line to a desired transformer 28. A lead 29 extends from the transformer 28 and it connects by branch wires 30 to various rows of 25 seats such as A, B, C and D, these branch wires 30 being, in turn, connected by the conductors 26 to the seat switches 12. The aforementioned conductors 27 extend from the opposite sides of the switches 12, and each connects to a corresponding lamp 31 preferably located within an indicating box 32 and, of course, this vacant seat indicating box may be located somewhere at the rear of a theater where patrons and ushers can readily observe the same. From the remaining 35 sides of the lamps 31 branch wires 33 extend to connect to a return wire 34 to the transformer 28.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

45 In combination, a chair having a hinged yieldingly raised seat, and side members having inwardly disposed ledges to support the seat when depressed, said seat having an inset formed in the bottom thereof near one side, one ledge having an inward protrusion directly below said inset, an insulating disc having a conducting ring on its under side and secured to the top wall of said inset, an insulating cup mounted on the protrusion and receivable in the inset when the seat 50 is depressed, and spaced arcuate spring contacts mounted in the cup and engageable by the conducting ring when the seat is depressed, said protrusion and said cup being centrally apertured to permit passage of conductor wires there- 55 through to said contacts.

ORVILLE KENNETH SILVER.
